US0D1072361S

(12) **United States Design Patent** (10) **Patent No.:** **US D1,072,361 S**
(45) **Date of Patent:** **** Apr. 22, 2025**

(54) **KNEE PAD**

(71) Applicant: **Shenzhen Keepfit Technology Co., Ltd.**, Shenzhen (CN)

(72) Inventors: **Lijun Wan**, Shenzhen (CN); **Ye Shen**, Shenzhen (CN)

(73) Assignee: **Shenzhen Keepfit Technology Co., Ltd.**, Shenzhen (CN)

(**) Term: **15 Years**

(21) Appl. No.: **29/852,610**

(22) Filed: **Sep. 8, 2022**

(51) **LOC (15) Cl.** **02-99**

(52) **U.S. Cl.**

USPC **D29/121.1**

CLAIM

The ornamental design for a knee pad, as shown and described.

DESCRIPTION

FIG. 1 is a top perspective view of a knee pad showing our new design;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in the drawings depict the portions of the knee pad that form no part of the claimed design.

1 Claim, 8 Drawing Sheets
